UNITED STATES PATENT OFFICE.

CHARLES O. WILDER, OF SOUTH BEND, INDIANA.

FUEL-OIL BURNER.

SPECIFICATION forming part of Letters Patent No. 429,205, dated June 3, 1890.

Application filed March 10, 1890. Serial No. 343,257. (No model.)

To all whom it may concern:

Be it known that I, CHARLES O. WILDER, a citizen of the United States, residing at South Bend, in the county of St. Joseph and State 5 of Indiana, have invented a new and useful Improvement in Fuel-Oil Burners, of which the following is a specification.

My invention relates to an improvement in that class of fuel-oil burners in which the oil 10 in a finely-divided state is atomized by means of an air-blast.

The object of my improvement is to provide in such a burner a simple and durable means for finely dividing the oil, so as to distribute 15 it evenly throughout the air-current, and thereby thoroughly charge the air-current with atomized oil.

The accompanying drawings illustrate my invention.

20 Figure 1 represents a longitudinal section of the burner. Fig. 2 represents a transverse section at *a*. Fig. 3 is a transverse section at *b*.

A is an air-chamber formed of an ordinary 25 *T*-coupling.

B is the air-pipe, through which a strong current of air is driven, by means of a fan or other suitable means, into chamber *A*.

C is a section of pipe which is screwed into 30 one end of chamber *A*, and forms the jet or burner proper. The opposite end of chamber *A* is closed by a cap *D*, in the center of which is mounted a small pipe *E*, which extends centrally and longitudinally through 35 the chamber, and is connected at its outer end with a source of oil-supply.

F is a spiral wire brush formed by introducing between twisted wires *h h* a continuous series of straight radial wires *i i* in the 40 manner well known in making wire brushes. A portion of the twisted wires *h h* is left at one end without the radial wires *i*, and this portion is inserted in the inner open end of the oil-pipe, and is secured therein in such a 45 manner as to only partially close the pipe. This is preferably done by inserting the wires *h h* in the pipe along one side thereof, and

then crimping the pipe longitudinally, so as to embrace and hold the wires and also leave at the opposite side of the pipe the inclosed 50 portion *j*. The radial wires *i* extend diametrically across the interior of pipe *C* and form a spiral line along nearly its entire length.

L is a sliding damper arranged to control the flow of air through pipe *B*.

In operation air is supplied in a strong current through pipe *B*, and passes through chamber *A* and pipe *C*. Oil is supplied through pipe *E*, and the oil passing through 6c opening *j* flows along the wires *h* and the radial wires *i*, thus exposing a large amount of oil-covered surface to the action of the air-current, which is thereby quickly and evenly charged with the oil-vapor, which is ignited at the mouth of pipe *C*.

65 I claim as my invention—

1. An oil-burner comprising a chamber having an air-inlet pipe, a burner proper consisting of a pipe connected at one end with said chamber, an oil-pipe passing through 70 said chamber, an oil-distributer secured in the inner end of the oil-pipe and extending along the interior of the burner-pipe, said distributer consisting of two or more wires twisted together to form a central core, and a 75 series of radial wires embraced by said twisted wires and arranged spirally thereon, all combined substantially as and for the purpose set forth.

2. In an oil-burner, the combination of the 8c air-chamber, the burner-pipe extending therefrom, the oil-pipe extending through the air-chamber, and the oil-distributer consisting of a central core secured within the open end of the oil-pipe, so as to partially close it, said core 85 extending along the interior of the burner and provided with a series of radial wires spirally arranged thereon, substantially as set forth.

CHARLES O. WILDER.
